UNITED STATES PATENT OFFICE

HENRY J. THEIS, OF DAYTON, OHIO, ASSIGNOR TO DAYTON SCALE COMPANY, OF DAYTON, OHIO, A CORPORATION OF NEW JERSEY

SLICING MACHINE

Application filed March 29, 1930. Serial No. 439,939.

This case is an improvement on application Serial No. 425,184, assigned to the assignee of the instant case and relates to detail improvements in a food slicer.

Particularly, it is an object of the invention to provide an article feeding device with improved means to guide it for movement relative to the knife.

More specifically, the object is to provide a novel anti-friction connection between the feeding device and the support therefor.

Other objects and advantages will be hereinafter set forth in the accompanying specification and claims, and shown in the drawings, which by way of illustration show what is now considered to be the preferred embodiment of the invention.

Fig. 1 is a view of the machine from the feeding side;

Fig. 2 is a rear view of the clamp;

Fig. 3 is a vertical section through line 3—3 of Fig. 2;

Fig. 4 is an enlarged view of the rear of the slide assembly;

Fig. 5 is a section on line 5—5 of Fig. 6;

Fig. 6 is a section through the ball race assembly on line 6—6 of Fig. 5;

Fig. 7 is a section on line 7—7 of Fig. 2; and

Fig. 8 is a detail of the clamp.

Referring to Fig. 1, the machine includes a rotary knife 10 driven by belt 11. At the side of the knife is a gage plate 12 adjustable to determine the thickness of slice to be cut by the knife. The base 13 of the machine has a pair of posts 14, one at each end for carrying a round rail 15. A rectangular rail 16 is fixed to the base below rail 15.

The article holding carriage 17 is provided with a hole through which rail 15 passes. A vertical extension 18 of the carriage has journalled at its end, a roller 19 engaging the side of rectangular rail 16.

The carriage 17 is thus guided for movement past the knife by rails 15 and 16.

The carriage 17 has fixed to the rear of the side nearest the knife by means of screws 24, a flat rail 25 running parallel to said side.

Rail 25 has V-shaped grooves 26 in the upper and lower edges, the grooves serving to

guide a clamp carrier 27 for movement towards the plane of the gage plate as will be more fully described below.

The lower end 28 of the carrier 27 has fastened to the back side thereof upper and lower bearing assemblies comprising solid bars 30 having one edge 31 formed with V-shaped grooves 32 complementary to the V-shaped grooves 26 of rail 25. The opposite edge 33 is formed with a bullet shaped groove 34. The ends of the bar are slotted out leaving projecting sides terminating in arcuate edges. Holes 35 are drilled through the end side portions and located so that a semi-circular cavity is formed in the solid portion of the bar contiguous to the slotted end. The grooves 32 and 34 are thereby joined by a concave semi-circular wall. Bushings 36 when fitted in the holes 35 complete a continuous track formed by parallel grooves 32 and 34 and the sides of the bushings 36 extending into the slotted outer ends of the bar. A jacket 37 is secured to the edges 33 and the arcuate ends of the sides of the bar 30, leaving only groove 32 exposed. The continuous track constitutes a raceway for balls 39 and when a race assembly is on the machine, the balls ride between groove 32 in the bar 30 and groove 26 in track 25. The strip 37 terminates at each end in a V-shaped projection 40 extending into the V-shaped groove 26 in order to prevent balls 39 from riding out of the cooperating grooves.

The lower raceway is fixed to the clamp bracket end 28 by screws 43 each of which has a round portion 44 (Fig. 3) journalled in a hole in the end 28, an eccentric portion 45 adjacent the round portion and seated in a bushing 36 of the lower race assembly and a threaded portion 46 to coat with nuts 47 to fix the screw to the end 28. By turning the screw, the eccentric portion 45 thereof serves to move the lower raceway closer to or further from the rail. In this manner, the proper adjustment between the lower raceway and the rail is obtained.

After adjustment, the screws may be prevented from turning by a socket set screw 48 engaging the side of the round portion 44 of screw 43. The upper raceway is non-adjust-

ably held to the clamp end 28 by screws 49 and socket set screws 50 engaging the sides of screws 49.

The clamp bracket 27, slide 25, and raceways when assembled form a single, replaceable unit held to the carriage solely by screws 24. The clamp bracket has at its upper end a post 51 through which is an opening in which is slidable a bar 52 having a handle 53 and carrying at its lower end a spiked clamp plate 54. The clamp plate is adapted to coact with a spiked plate 55 removably secured to the ledge 56 of clamp bracket 27 by knurled hand screws 57. The screws 57 coact with open bayonet slots 58 in the upper end of the spiked plate 55. The slots permit adjustment of the plate 55 at right angles to the gage plate and are open to provide means for easily removing the plate 55 from the support 56.

Movement of the bracket towards the knife is adjustably limited by contact of the end portion 28 with a screw 59 threaded into the carriage at the side adjacent the knife and retained in adjusted position by a locknut 60. Between spiked plate 55 and the surface of the carriage 17 is a porcelainized tray 61 (Figs. 1 and 7) to the bottom of which are fixed nuts 62 cooperating with screws 63 passing through the elongated apertures 64 in the sides of the carriage 17. The elongation of apertures 64 enables the porcelainized tray 61 to be adjusted towards the plane of the knife.

Both the latter adjustment and the adjustment of the travel of clamp bracket by means of screw 59 are necessary to provide proper clearance between the tray and clamp parts and the gage plate and knife during movement of the carriage past the knife.

In operation, an article is placed on the carriage 17 and clamp plate 54 adjusted to clamp the article against clamp plate 55 and porcelainized tray 61. The clamp bracket 27 is then moved towards the gage plate by means of handle 53 to bring the article into engagement therewith. The carriage is then moved past the knife during which a slice is cut by the knife.

It will be understood that the novel guiding means for clamp carrier 27 is not restricted to use with a clamp movable transversely to the knife but may be used to guide an element such as carriage 17 movable parallel to the plane of the knife.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claim:

In a slicing machine, a knife, a carriage for traversing the knife, an article feeder, upper and lower coacting guiding means provided on the carriage and the feeder for guiding the feeder transversely of the knife plane, and means for adjusting the upper and lower guiding means relatively towards and away from each other to provide the proper riding fit between the carriage and the feeder.

In testimony whereof I hereto affix my signature.

HENRY J. THEIS.
